No. 743,119.

PATENTED NOV. 3, 1903.

J. H. WATSON, JR.
COMBINED RULER AND BLOTTER.

APPLICATION FILED DEC. 16, 1902.

NO MODEL.

UNITED STATES PATENT OFFICE.

JAMES HENRY WATSON, JR., OF NEW YORK, N. Y.

COMBINED RULER AND BLOTTER.

SPECIFICATION forming part of Letters Patent No. 743,119, dated November 3, 1903.

Application filed December 16, 1902. Serial No. 135,414. (No model.)

To all whom it may concern:

Be it known that I, JAMES HENRY WATSON, Jr., a citizen of the United States, residing at New York, county of New York, and State of New York, have invented a new and useful Improvement in a Combined Ruler and Blotter, of which the following is a specification.

The object of my invention is to provide a ruler having means by which a strip of blotter may be readily attached thereto or removed therefrom and having a handle placed to be conveniently grasped by the left hand of the operator in position to hold the front edge of the ruler parallel to the plane of the front of the operator's person.

Referring to the drawings, Figure 1 is a perspective view of the ruler and blotter. Fig. 2 is a view of a longitudinal section, and Fig. 3 is a view of a transverse section of the same.

In the drawings reference character 1 indicates the plate portion of my device, such plate being preferably formed of a light and non-corrosive metal, such as aluminium. The long edges 1^a, or what I term the "side" edges, of such plate are turned downwardly and under the plate, whereby a longitudinal channel is formed in the under surface of the plate, care being taken to form each bent edge in a straight line to provide ruling edges. Such edges, if desired, may bear marks indicating the subdivisions for linear measurement. The end portions of the plate are cut away on each side to form central tongues 2 and 2', and each tongue is bent upwardly and backwardly or reversely, as shown, to project over along the central upper surface of the plate. A handle 3 is attached to the upper surface of the plate, about midway between its ends, to project upwardly from the plate

and from the straight-edge thereof, the axis of such handle making an oblique angle with the straight-edge, so that when the plate is held in front of the operator with the straight-edge parallel to the front of the operator's body the handle projects rearwardly to the left of the operator in position to be readily grasped by the operator's left hand. If desired, the position of the handle may be changed to project toward the operator's right hand or to project rearwardly at a right angle to the straight-edge.

On the under surface of the plate in the

channel formed as above stated is secured a pad 4, of felt or other similar substance. The blotting-strip 5 underlies such pad and is secured in position as follows: One end 5^a of the strip is inserted between the overlying tongue 2, and the top surface of the plate and the strip is then bent over such tongue, as at 5^b, and brought under the pad of felt at 5^c. The strip is stretched under the pad, and the remaining end of the strip is turned, as at 5^d, over the end of the plate and the upwardly-projecting portion of the tongue 2' and at 5^e over the top of the tongue, and the portion 5^f, projecting beyond such tongue, is doubled on itself and tucked under the tongue, the end 5^g of the strip projecting outwardly beneath such tuck.

By unfolding the lateral edges of the ruler-plate I am enabled to use a thin sheet metal, to which is thus imparted rigidity and sufficient flexibility to conform to the desired extent under pressure by the operator to the surface ruled, thus supplementing the purpose of the pad underneath in causing the blotter-strip to press against every portion of the line ruled.

The pad of felt may be secured in the channel either by an adhesive or by clamping the edges of the pad between the under surface of the plate and the under-turned side edges.

Having thus described my invention, I claim—

1. An article of manufacture comprising a plate having upwardly and reversely turned ends, and a blotter-strip secured to such plate by having its ends brought over and tucked under the upwardly and reversely turned ends of the plate.

2. A combined ruler and blotter comprising a plate having inturned edges and upwardly and reversely turned ends, a pad secured between the edges, and a blotting-strip secured below such pad, the ends of such strip being brought over and tucked under the upwardly and reversely turned ends of the plate.

3. A combined ruler and blotter comprising a plate having inturned side edges and upwardly and reversely turned ends, a pad secured between the edges of the plate, and a blotter-strip below such pad, one of the ends of such strip being secured to the plate, and the other end of the strip being brought over

and tucked under the upwardly and reversely turned end of the plate so that the strip end projects outwardly beneath such tuck.

4. An article of manufacture comprising a metal plate provided with means whereby a blotting-strip may be attached thereto and having under-turned lateral edges forming a longitudinal channel in the under surface, and a strip of felt material located in such channel.

5. A combined ruler and blotter comprising a plate having a straight-edge and upwardly and reversely turned ends, a blotter-strip secured to such plate, the ends of the strip being brought over and tucked under the up-

wardly and reversely turned ends of the plate, and a handle secured to the plate, the handle projecting upwardly from and at an oblique angle to the straight-edge of the plate.

6. An article of manufacture comprising a metal plate provided at its ends with means whereby a blotting-strip may be attached thereto and having under-turned lateral edges forming a longitudinal channel in the under surface, and a strip of felt material located in such channel.
